UNITED STATES PATENT OFFICE.

LAIRD W. NEVIUS, OF TOLEDO, OHIO.

INHALER.

SPECIFICATION forming part of Letters Patent No. 279,265, dated June 12, 1883.

Application filed May 3, 1883. (No model.)

To all whom it may concern:

Be it known that I, LAIRD W. NEVIUS, a citizen of the United States, residing at Toledo, county of Lucas, and State of Ohio, have invented a new and useful Improvement in Gas-Inhalers, of which the following is a specification.

The inhalers now in use have the exhaling-valve on the upper part of the mouth-piece or on the inhaling-pipe, so that the gas used by a patient is discharged in an upward direction. This exposes the operator to the effects of the impure gas and renders its administration in a certain degree injurious to health.

The object of my invention is to provide a simple and effective inhaler free from this objection, and one that will have the additional advantage of being held to the mouth and operated upon by a single hand, leaving the other free for instant use when a sufficient quantity of gas has been administered. I secure these advantages by combining with the mouth-piece of an inhaler an exhaling and inhaling tube having suitable valves for the inspiration and expiration of the breath and gas, the exhaling-tube being so placed upon the mouth-piece as to project horizontally therefrom, and, by means of the exhaling-valve at its end, securing, with each expiration of the breath, the discharge of the gas in a line, as near as possible, to the line of the breath from the mouth. The inhaling-tube is provided with a slide-valve having a rubber seat, said valve acting by pressure upon its head, opening thereby, and closing by means of a rubber or spiral spring attached to the valve-slide and fitting over the inhaling-tube.

Figure 1 is a sectional view of my inhaler. Fig. 2 is a cross-section of inhaling-pipe, drawn upon line *x* in Fig. 1, showing slide-valve closed. Fig. 3 is a cross-section of inhaling-pipe, drawn upon line *x* in Fig. 1, showing slide-valve opened.

Similar figures of reference indicate corresponding parts.

In Fig. 1, 2 is the rubber mouth-piece, which fits close to the face; 3, the metallic collar or hood into which the mouth-piece fits; 4, the horizontal exhaling-tube; 5, the exhaling-valve at the end of said tube; 6, the cap, with central opening and perforated sides, fitting over

and protecting the exhaling-valve; 7, the inhaling-tube; 8, the inhaling-valve; 9, the slide-valve; 10, a section of rubber tube fitted within the inhaling-pipe and forming the seat of the slide-valve.

In Fig. 2, 9 is the slide-valve in a closed position; 11, the opening; 7, the inhaling-tube; 12, the rubber or spiral spring fitting around the inhaling-tube and held in position by the grooved shoulder 13 on the end of the valve-slide.

It will be seen by the construction shown that the gas, after being used, will be discharged in a direction away from the operator, and that the inhaler can readily be held and operated upon by one hand. By taking it in either hand, the operator's thumb or finger upon the head of the valve-slide, it is ready for the administration of gas. Pressure upon the slide will bring the opening 11 (shown in Fig. 2) in a line with the inhaling-tube, as shown in Fig. 3, thus allowing a free flow of gas from the receiver. When sufficient gas has been administered, removing the pressure from the slide or dropping the inhaler instantly cuts off the supply of gas. In Fig. 3 the valve is shown as open.

By placing the exhaling-valve in the line of the breath from the mouth I not only secure protection to the operator, but the best possible action upon the exhaling-valve by direct pressure with each expiration of the gas, said pressure at the same instant closing the inhaling-valve located immediately below it.

The exhaling and inhaling tubes form a junction at the neck of the mouth-piece, which they enter in the form of a single pipe.

The mouth-piece should be of rubber or other flexible material, the hood around its neck, the inhaling and exhaling pipes, and slide-valve should be of metal or other suitable material, and the exhaling and inhaling valves of thin rubber. Sections of rubber tube properly fitted within the pipes will form the necessary valve-seats.

The slide-valve operates through and across the inhaling-tube by means of slots on either side of the tube, through which the slide moves. At the end of the slide opposite the head, where pressure is to be applied, is a grooved shoulder, into which the rubber ring or spring

is placed to hold it in proper position upon the tube.

What I claim as my invention, and desire to secure by Letters Patent, is—

5 1. In combination with the mouth-piece and inhaling-pipe of a gas-inhaler, a horizontal exhaling-tube with exhaling-valve at its end, substantially as and for the purposes set forth.

10 2. In combination with the mouth-piece of an inhaler, an inhaling-pipe with a slide-valve having circular spring attachment thereon, and an exhaling-pipe with discharge-valve at its

end, protected by a cap having a central spring, said pipe projecting horizontally from the neck of the mouth-piece, and forming a junction 15 with the inhaling-pipe near its base, substantially as and for the purposes set forth.

In testimony whereof I have signed my name to this specification in the presence of two subscribing witnesses.

LAIRD W. NEVIUS.

Witnesses:

THOMAS D. CONE,

CLAYTON W. EVERETT.

It is hereby certified that in Letters Patent No. 279,265, granted June 12, 1883, upon the application of Laird W. Nevius, of Toledo, Ohio, for an improvement in "Inhalers," an error appears requiring correction as follows: the word "spring," in line 5 of the second clause of claim of the printed specification forming a part of said patent, should read "opening;" and that the specification should be read with this correction therein to make it conform with the record of the case in the Patent Office.

Signed, countersigned, and sealed this 26th day of June, A. D. 1883.

[SEAL.]

M. L. JOSLYN,
Acting Secretary of the Interior.
